BEACH SANDAL

Thomas H. Doherty, South Bend, Ind., assignor to United States Rubber Company, New York, N. Y., a corporation of New Jersey

Application February 3, 1956, Serial No. 40,033

Term of patent 14 years

(Cl. D7—7)

Fig. 1 is a perspective view of a beach sandal showing my new design;

Fig. 2 is a side elevational view; and
Fig. 3 is a rear elevational view.

I claim:

The ornamental design for a beach sandal, as shown.
